UNITED STATES PATENT OFFICE.

EDWARD H. BELDEN, OF TOLEDO, OHIO, ASSIGNOR TO BELDEN PATENTS INCORPORATED, OF TOLEDO, OHIO, A CORPORATION OF OHIO.

SLEEVE-VALVE TWO-CYCLE MOTOR.

Application filed December 21, 1923. Serial No. 682,010.

My invention relates to an internal combustion motor and particularly to a motor of the two-cycle sleeve-valve type.

My invention has for its object to provide such a motor which will work reliably and accurately as to charging action and without unnecessary friction. Other features of my invention will appear as the description proceeds.

10 In the accompanying drawings, illustrating one form of motor embodying my invention, Fig. 1 is a vertical cross section of such a motor; Fig. 2 is a view partly in section and partly in elevation of a portion of 15 the device viewed from the right of Fig. 1, and Figs. 3, 4 and 5 are diagrammatic views showing different positions of the moving parts.

On a crank case 9 there are mounted cylinders 10 and 11. In the working cylinder 10 there is a piston 12 and in the charging cylinder 11 there is a piston 13. A crank shaft 14 is mounted within the casing and has a crank 15 connected by a rod 16 to the 20 pivot 17 of the piston 12. Projecting from near the crank end of the rod 16 are ears 18 in which is mounted a pivot 19. A rod 20 connects the pivot 19 with the pivot 21 of piston 13. Within the working cylinder 10 25 there is a sleeve valve 22. The crank shaft has an eccentric 23 beside the crank 15. Ears 24 project from the sleeve 22 and are connected to the eccentric by a rod 25. A head 26 has a member projecting into the 30 end of cylinder 10 and spaced from the walls of the cylinder so as to leave an annular space 27. There is also provided a recess 28, forming a combustion chamber, and the usual spark plug 29 enters this chamber. The outer end of the charging cylinder 11 35 is closed by a cap 30.

There is an inlet port 31 in the side of the charging cylinder in position to be uncovered by the piston 13 during its downward stroke. There is a connecting port 32 between the closed ends of the two cylinders, and outlet ports 33 and 34 open from the working cylinder. The sleeve valve 22 has an inlet port 35, registering at proper intervals with port 32, and exhaust ports 36 and 37, registering at proper intervals with exhaust ports 33 and 34.

While I have shown in detail but one working cylinder and its accompanying charging cylinder, it will be understood that

as many as desired may be connected to the same crank shaft, and I have indicated in Fig. 2 another charging cylinder with its piston 41 and rod 42, which may be connected to a crank 43, and the sleeve valve 44 with its rod 45, which may be connected to an eccentric, not shown.

The general operation of the motor will readily appear from the structure described, but for greater convenience may be briefly 65 stated in connection with the diagrammatic views.

In the position shown in Fig. 1, a charge will have been compressed and fired within the working cylinder and the working stroke 70 is just beginning. As the piston 12 moves downward, the sleeve moves with it at nearly the same speed. As will be seen from Fig. 3, the crank pin 15 travels in a circle 46, while the center 47 of the eccentric strap 75 travels in a circle 48 which is only about one-third the diameter of the circle 46; but at the start of the explosion stroke when the pressure within the cylinder is greatest the eccentric is in such a position in its path 80 that its vertical travel is fairly rapid, while the crank pin 15 is in the portion of its travel where the resultant motion of the piston 12 is the slowest, and consequently the sleeve 22 travels for a time at nearly as great speed 85 as the piston 12.

Port 35 is well below the port 32 before the top of piston 12 is lowered to that point, so the inlet port is sealed on the working stroke. Likewise, the port 37 is below the 90 port 34 before the top of the piston reaches that point, so that the exhaust port 34 is sealed during the downward stroke of the piston, and exhaust does not occur until the piston has lowered sufficiently to open the 95 exhaust through ports 36 and 33. Upon the upward stroke of the piston, the ports 37 and 34 will register until the piston crosses the port 37 in the manner shown in Fig. 5.

While the piston 12 is descending, piston 100 13 also descends and rarefies the gases in cylinder 11. When the descent of piston 13 uncovers port 31, fuel gases rush in and charge the cylinder. During the upward stroke, the piston 13 compresses the charge 105 within the cylinder, and by the time the port 35 begins to register with port 32, as shown in Fig. 5, the gases within cylinder 11 will be sufficiently compressed to pass rapidly through the opening into cylinder 10. 110

While I prefer to open the inlet through ports 32 and 35 slightly before the complete closure of the exhaust through ports 37 and 34, so as to blow out any remaining exhaust gases, this is not necessary, as the amount of exhaust gases within the cylinder 10 is comparatively small at this time and, when cooled by the incoming charge, does not make any material difference with the operation of the motor.

As will be seen, the charging piston 13 reaches the upper limit of its stroke before the working piston reaches its highest point. The ports 32 and 35 are arranged to close at about the time when the piston 13 reaches the upper limit of its travel, and piston 12 then continues to further compress the charge within cylinder 10. This allows any desired advancement of the spark.

By my construction it will be seen that the ports of the working cylinders are effectually controlled by the sleeve valve, and this operation allows the gases to be exhausted during a considerable portion of the stroke of the piston and the charge to be introduced almost entirely while the exhaust ports are opened. This results in a two-cycle engine which has sufficient time for exhaust and charging without danger of blowing any of the charge out of the exhaust and without shortening in the least the working stroke. By the use of the separate charging piston, the charge may be introduced under any desired pressure, the diameter of the charging cylinder being so proportioned to that of the working cylinder as to secure the size of charge desired.

As will be noted, the shaft 14 is at one side of the axial line of the working cylinder and with the shaft rotating in the direction indicated by the arrows the working stroke takes place while the crank is on the side of the shaft towards the axial line of the working cylinder. The result is that there is less angularity of the piston rod 16 during the working stroke than there would be if the shaft were mounted in the axial line of the cylinder. This is a particular advantage when a sleeve is used, as it lessens the liability of the sleeve to be cramped by the side pressure of the piston.

In the arrangement shown, there is practically no extra friction caused by the use of the sleeve, because the sleeve is always moving in the same direction as the piston ex-

cept for short intervals at the top and bottom of the stroke when the speeds of both sleeve and piston are very low and their difference in direction does not result in any considerable friction.

While there may be considerable variation in the size, location and arrangement of ports and the consequent timing, it will be seen from the drawings that a satisfactory arrangement may be made with the sleeve eccentric advanced less than thirty degrees ahead of the crank. An advancement of thirty degrees would result in the travel of the piston and sleeve in opposite directions through about one-fifteenth of the distance traveled, while an advancement of even forty-five degrees would result in such opposed travel for less than one-sixth of the total distance.

A sleeve within the charging cylinder would control the port 32 as well as the one shown, and might be made to control the intake also, if desired; or sleeves might be provided in both cylinders and control intake, transference and exhaust.

Various other changes in the construction and arrangement of parts within the scope of the appended claims may be made without departing from the spirit of my invention.

What I claim is:—

1. In an internal combustion motor, a working cylinder and piston, a charging cylinder and piston at one side of and parallel with the working cylinder, there being a port connecting the cylinders, a sleeve valve governing the port, a crank shaft, means connecting the pistons to a crank on the shaft, an eccentric on the shaft, and a link connecting the eccentric to the sleeve.

2. In an internal combustion motor, a working cylinder and piston, a charging cylinder and piston at one side of and parallel with the working cylinder, there being a port connecting the cylinders, a sleeve valve surrounding the piston within the working cylinder, a crank shaft, means connecting the pistons to a crank on the shaft, an eccentric on the shaft, and a link connecting the eccentric to the sleeve, the eccentric being advanced less than forty-five degrees ahead of the crank.

In testimony whereof I have hereunto signed my name to this specification.

EDWARD H. BELDEN.
